UNITED STATES PATENT OFFICE

LEON D. SLADE AND ALTON P. SLADE, OF ROCHESTER, NEW YORK, ASSIGNEES TO
GLEASON WORKS, OF ROCHESTER, NEW YORK, A CORPORATION OF NEW YORK

TEMPERING-MACHINE.

1,126,307.

Specification of Letters Patent.

Patented Jan. 26, 1915.

Application filed January 16, 1913. Serial No. 742,390.

To all whom it may concern:

Be it known that we, LEON D. SLADE and ALTON P. SLADE, both of Rochester in the county of Monroe and State of New York, have invented certain new and useful Improvements in Tempering-Machines; and we do hereby declare the following to be a full, clear, and exact description of the same, reference being had to the accompanying drawings, forming a part of this specification, and to the reference-numerals marked thereon.

The invention relates to improvements in tempering machines, being designed more particularly with reference to its use in connection with the tempering of gear wheels and articles having generally a similar formation, and it has for its object to provide a machine of this type which will permit of tempering the metal after it has been heated for case hardening, and at the same time prevent any irregularities that would otherwise be caused by the contraction of the metal upon cooling.

Another object of the invention consists in providing a novel construction and arrangement of parts whereby the articles may be readily positioned for the tempering process, after they are taken from the furnace, the parts being so disposed as to enable the article to be positioned quickly, and at the same time with great accuracy, so that when cooled it will be true in every respect and require no further pressing.

To these and other ends the invention consists in certain improvements and combinations of parts, all as will be more fully described, the novel features being pointed out in the claims at the end of the specification.

In the drawings: Figure 1 is a vertical sectional view of a machine constructed in accordance with a preferred embodiment of our invention; Fig. 2 is an enlarged sectional view, showing portions of the upper and lower die members with a gear wheel positioned therebetween; Fig. 3 is a plan view of the lower die member, with a gear in position thereon, and Fig. 4 is an enlarged vertical sectional view through the die members when in operative relation, at the limit of their downward movement.

Similar reference numerals throughout the several figures indicate the same parts.

55 In the present embodiment of our in-

vention, there is provided a frame embodying a base which comprises an outer wall 1 arranged in spaced relation to an inner wall 2 forming the oil reservoir 3. The base is formed at the top with an annular wall 4 disposed in spaced relation surrounding the top of the reservoir 3 and attached to said wall 4 are standards 5 which support at their upper ends the cylinder 6 for a purpose that will presently be described.

7 designates the upper die member which is adapted to engage a gear wheel or other article upon the lower die member, as will presently be described, and is suitably attached to a head 8, the latter being fixed upon a plunger or piston rod 9 which carries the piston 10 traveling in the cylinder 6. The cylinder 6 is connected by means of the pipe 11 with a suitable source of fluid pressure for effecting downward movement of the piston, and the weight of the upper die member and the parts connected thereto is counter-balanced by an annular weight 12 surrounding the cylinder 6 and connected to the head 8 by means of the cables 13 which are guided by the pulleys 14, the latter being mounted on the arms 15. It is desirable to effect a slightly yielding engagement between the upper die member and the article, and to this end the die member 15 carries a yielding annular ring 16 which is disposed in a suitable recess, being held in position by a series of bolts 17, while 18 are springs surrounding said bolts and serving to hold the ring with the required pressure against the article, and at the same time permitting it to yield slightly when necessary. The upper die member is cut away to afford a recess which co-operates with the toothed face of the gear, and is provided with the vertically extending openings 19 which permits passage of the oil, as will be explained hereinafter. Arranged centrally of the upper die member 7, and surrounding the piston rod 9, is a yieldable element or expander 20 which is provided with a conical face 21, and is supported upon the springs 22, the die member and yieldable element 21 being provided with co-operating shoulders indicated at 23 to limit their relative movement. The die member 7 is attached to the head 8 by means of bolts 24 or in any other convenient manner.

25 designates the lower die member which is normally disposed just above the top of

the reservoir 3, as shown in Fig. 1, and is supported upon the top 26 of the sleeve 27 which surrounds and is guided upon the casing 28 arranged centrally at the bottom of the oil reservoir. The lower die member is provided with a series of openings 29 to permit passage of oil therethrough. The top 26 of the sleeve 27 is provided with a central bushing 30, and 31 is a perforated basket attached centrally to its lower face. The lower die member is provided with an expandible gripping device for the purpose of engaging the inner edge of the article with yieldable tension, and to this end, said expandible gripping device preferably comprises a series of independently movable segmental grippers, designated at 32, each of which comprises a base, an overhanging shoulder 33 which engages the article, as shown in Fig. 4, and a cam surface 34 by which it is moved into engagement with the article. The gripping device just described may be formed by taking a ring of the desired cross sectional contour and cutting it into the necessary number of segmental portions, the lower die member being recessed or cut away at 35 to afford a seat for the grippers.

36 is a removable ring arranged in a recess in the lower die member and adapted to support the gear wheel. For gears or other articles of different sizes, different rings may be substituted according to the height required.

In the operation of the machine, the article while heated, is placed upon the lower die member, resting upon the ring 36, in a manner substantially as shown in Fig. 1. The upper die member is then lowered, whereupon the lower end of the plunger 9 comes into engagement with the movable grippers 32, to center the article. They are then engaged by the conical expander 21, which causes the inner edge of the gear to be engaged all around at points which are equal distances from the center. The article is thus accurately centered upon the lower die member just previous to the application of pressure. The parts are so arranged that immediately following the centering of the gear, the upper die member is forced hard against the same, and upon further operation, both of the die members and the article are lowered into the oil reservoir, causing the oil to spout upwardly through the openings in the die members and to come in contact with all portions of the article being tempered. Upon cooling, a certain amount of contraction in the metal takes place, causing a change in the diameter of the article, and this is taken up by the springs 22 which enable the expander 21 to slightly change its position with relation to the expandible gripping device on the lower die member, so that the grippers may follow the inner edge of the gear closely. By this means,

the article is always centered and there is no chance for any irregularities to occur, owing to changes in the metal upon cooling.

The downward movement of the sleeve 27 is resisted by the annular weight 37 which is connected with the sleeve by means of cables 38 passing over the pulleys 39 which are suitably mounted on the standards 5. The weight 37 is sufficiently heavy to cause the die members to engage each other with considerable pressure before they move downwardly into the oil bath.

40 is a pipe leading to the reservoir 3, through which oil may be supplied to maintain a circulation, and 41 is an over flow pipe connecting with the passage 42 which surrounds the upper end of the oil reservoir.

We claim as our invention:

1. In combination with a die member adapted to engage an article, a second die member for engaging the opposite surface of said article, one of said die members including an expandible gripping device for engagement with the article, and a yieldable element in the other die member arranged for coöperation with the expandible gripping device to force the latter into engagement with the article.

2. In combination with a lower die member adapted to move vertically, of an upper die member, means operating on the upper die member for first bringing it into engagement with an article on the lower die member and subsequently moving both die members together, an expandible gripping device on the lower die member, and a yieldable element on the upper die member arranged to coöperate with said expandible gripping device.

3. In combination with a lower die member adapted to move vertically and having a plurality of openings therein, of an oil reservoir in which said die member moves, an upper die member having a series of openings therein and adapted to be moved into engagement with an article on the lower die member, means for imparting downward movement to the upper die member, means connected to the lower die member for retarding its downward movement, and a yieldable element carried by the upper die member and coöoperating with an expandible gripping device on the lower die member.

4. In combination with an oil reservoir, of a lower die member movable vertically within the reservoir and normally positioned above the top thereof, an expandible gripping device arranged on the lower die member, an upper die member, a yieldable member carried by the upper die member for coöperation with the expandible gripping device, and means for moving said upper die member into engagement with an article on the lower die member, simultaneously expanding said gripping device, and subse-

quently lowering both die members into the oil reservoir.

5. In combination with a lower die member having vertical movement, of a plurality of movable grippers carried thereby and provided with inclined surfaces, and an upper die member movable into engagement with an article on the lower die member, the upper die member including a vertically yieldable expander adapted to engage said inclined surfaces of the grippers.

6. In combination with an oil reservoir, of a lower die member movable vertically within the reservoir and normally positioned above the top thereof, a plurality of movable grippers carried by the lower die member having inclined surfaces, an upper die member movable into engagement with an article on the lower die member, the upper die member carrying a vertically yieldable expander adapted to engage said inclined surfaces on the grippers, and a yieldable ring mounted on the upper die member and surrounding said expander.

25 7. In combination with a lower die member adapted to move vertically and having a plurality of openings therein, of an oil reservoir in which said die member moves, an upper die member having a series of openings therein and adapted to be moved into engagement with an article on the lower die member, means for imparting downward movement to the upper die member, means connected to the lower die member for retarding its downward movement, an expandable gripping device on the lower die member, and an element carried by the upper die member and coöperating with said expandable gripping device.

40 8. In combination with an oil reservoir, of a lower die member movable vertically within the reservoir and normally positioned above the top thereof, an expandable gripping device arranged on the lower die member, an upper die member, means carried by the upper die member for coöperation with

the expandable gripping device, and means for moving said upper die member into engagement with an article on the lower die member, simultaneously expanding said gripping device, and subsequently lowering both die members into the oil reservoir.

5. In combination with a lower die member having vertical movement, of a plurality of movable grippers carried thereby and provided with inclined surfaces, an upper die member movable into engagement with an article on the lower die member, the upper die member including an expander adapted to engage said inclined surfaces of the grippers.

10. The combination with a die member for supporting an annular article, a second die member for engaging the opposite surface of said article, one of said die members including an expandable gripping device for engaging the inner edge of the article and an element on the other die member coöperating with the expandable gripping device to force the latter into engagement with the inner edge of said article.

11. The combination with a lower die member having vertical movement, of an upper die member arranged to be brought into engagement with an annular article positioned on the lower die member, one of said members including an expandable gripping device for engaging the inner edge of the annular article, an element on the other die member coöperating with said expandable gripping device to force the latter into engagement with said inner edge of the article, means for imparting downward movement to the upper die member and means connected to the lower die member for resisting its downward movement.
